JAMES POWERS, OF NEW YORK, N. Y., ASSIGNOR TO POWERS ACCOUNTING MACHINE COMPANY, OF NEW YORK, N. Y., A CORPORATION OF DELAWARE.

CARD-ACCOUNTING MACHINE.

1,236,481.

Specification of Letters Patent. Patented Aug. 14, 1917.

Application filed August 21, 1915. Serial No. 46,703.

To all whom it may concern:

Be it known that I, JAMES POWERS, a citizen of the United States, residing in New York, in the county of New York and State 5 of New York, have invented certain new and useful Improvements in Card-Accounting Machines, of which the following is a specification.

This invention relates to card accounting 10 machines, and especially to means for positioning the zero type.

Among the main objects of the present invention, it is aimed to provide a device whereby only zero type will be positioned 15 for printing whenever no extension pin is actuated, whenever no card is fed through the machine, or whenever a card fed through the machine is out of alinement and whereby a single zero type will be positioned for 20 every row of pins in which no extension pin has been actuated.

Another object of the invention is to provide means whereby the zero type positioning means of each row will remain so positioned until a pin of another denomination in that row is actuated, which will release such zero type positioning means and permit the positioning of a type corresponding to the pin actuated.

Still another object of the invention is to provide an arrangement for releasing such zero type positioning means whenever it is desired to take a total and whereby, when the total has been taken, the zero type positioning means, as well as the other theretore-related mechanism, will automatically return to their initial position.

These and other features, capabilities and advantages will appear from the subjoined 40 detail description of one specific embodiment thereof, illustrated in the accompanying drawings, in which—

Figure 1 is a fragmental view, partly in section, showing the tabulating mechanism 45 of an accounting machine equipped with the present improvement.

Fig. 2 is a fragmental perspective showing the means for releasing and resetting the zero stop mechanism before and after taking 50 a total.

Fig. 2^a is a fragmental elevational view, showing parts of the mechanism illustrated in Fig. 2.

Fig. 3 is a fragmental view, partly in sec-

tion, showing the zero stop in stopping position.

Fig. 4 is a fragmental view in end elevation of parts of the mechanism shown in Fig. 3.

Fig. 5 is a fragmental perspective, partly in section, showing the zero stops.

Fig. 6 is a fragmental view in end elevation, similar to Fig. 4, but showing in addition the means for displacing the zero stops when it is desired to take a total.

In the embodiment shown, there is provided a lower frame A having a series of rollers 12 by means of which the cards to be recorded are fed into and discharged from between the die-plate 13 and the guide-plate 14. The plates 13 and 14 are correspondingly perforated, the upper ends of the analyzing pins 15 yieldably mounted in the pin-box 16, being disposed in the perforations of the guide plate 14, and the lower 75 ends of the extension pins 17 disposed in the perforations of the die-plate 13. The extension pins 17 are guided by the plates 18 and 19 and are equipped with upper rounded heads 20. The pin-box 16 is reciprocally 80 mounted thereby to actuate the pins 15 to analyze the card being treated. The pins 15, in the course of operation, finding perforations in the card being treated, will pass therethrough and actuate extension 85 pins 17 in alinement with them, which in turn will actuate stop pins 21 in alinement with such actuated extension pins, the stop pins 21 being mounted in the frame S.

The frame S is composed of end walls 22 and side walls 23. The end walls 22 of the frame S are provided with recessed seats 24 and 26 on opposing faces, in the front seat 24 of which the spacing plate 25 is positioned, and in the rear seat 26 of which the 95 spacing plate 27 is positioned, the spacing plates 25 and 27 mounting the guide-plates 28 and 29 correspondingly perforated to receive the stop pins 21. The stop pins 21 each have shoulders 30 at their upper portions which rest on the plate 29 and limit the downward movement of the pins 21, and each pin has a recess 31 in its lower portion, the stop pins 21, with respect to the recesses 31, being arranged in pairs of transversely 100 extending rows, the two rows of each pair having the recesses 31 disposed opposingly to receive the retracting bar 32 so that each

retracting bar 32 will serve to retract two pairs of said pins. The retracting bars 32 are supported by the frame members 33 suitably connected by the link 34 to actuating means not shown.

The stop pins 21 longitudinally of the frame S form rows of pins having ten pins each, the pin at the front end being the zero stop pin, and for purpose of description designated as 21^a, and the others in consecutive order from one to nine rearwardly, being the integer stop pins and designated as 21^b. Each of the stop pins 21 is disposed to register with one of the extension pins 17, which in turn is disposed to register with one of the analyzing pins 15. The perforations 35 (see Fig. 5) are round openings having notches at opposite ends, this conformation being provided in order to reduce friction on the stop pins 21 to its minimum.

Type carrying sectors 36 are provided one for each longitudinally extending row of stop pins 21, the upper ends of the first nine pins of each longitudinally extending row terminating at various lengths to form an arc whereby to facilitate the coöperation between the upper ends of the stop pins 21 and the stops 37 at the heels of the sectors 36, the travel of which stop pins 37 is through arcuate paths of movement. At the upper end of the rear spacing plate 27 there is provided a laterally extending stop bar 41 coöperating with the stops 37 of the sectors 36 when the "nine" stop pins 21^b are actuated.

Adjacent to each longitudinal row of stop pins 21, there is disposed a zero stop plate 38 having a pivotal pin 39 at the lower end of its front edge, and a pivotal pin 40 at the lower end of its rear edge. The pivotal pins 39 are journaled in the front spacing plate 25 and the pins 40 are journaled in the rear spacing plate 27. Each zero stop plate 38 has an enlarged upwardly extending portion 42 at its front end provided with a zero stop 43 at the rear of said portion 42 and a forwardly extending arm 44 which is bent as clearly shown in Fig. 5. On the outer face near the lower end of the front spacing plate 25, there are provided two screws 45 suitably spaced apart to form limiting stops and mount the plate 46. The plate 46 is provided with two recesses 47 cut into its lateral ends, the inner ends of which are spaced from one another a less distance than are the screws 45 spaced from one another, the screws 45 being disposed in said recesses and coöoperating therewith to permit the plate 46 to be transversely slidable. Near a lateral edge of the front spacing plate 25, in the present instance the inner edge, there is formed a pin 48 to which one end of a spring 49 is secured, the other end of the spring 49 being secured to a pin 50 on the plate 46 by means of which the

plate 46 is normally disposed adjacent to the pin 48. The upper end of the plate 46 is provided with a plurality of recesses 51 to permit the front extensions 44 to extend therethrough.

On the outer side of said plate 46, there is provided a plurality of flat springs 52 each of which is secured at one end by a plate 53 so that its other end, in the present instance its upper end, is strained against an extension 44 inside of the bent portion whereby the thereto-connected plate 38, inclined to one side which, in the present instance, is such that the outwardly extending stop 43 will lie in the path of movement of a stop 37 of a sector 36. From the foregoing, it is seen that the sectors 36 are normally maintained in a zero printing position by means of the stops 43. Each of the plates 38 is provided with a trough-like bend 54 to coöperate with the humps 55 of the stop pins 21^b. From this it will be seen that in the lower initial positions of the stop pins 21^b, the humps 55 will rest in the trough-like bends 54 permitting the plates 38 to be disposed in zero stopping position, but that when the stop pins 21^b are raised, their humps will strike the upper straight portions of the plates 38 and deflect the plates 38 out of zero stopping position and permit the sectors 36 to be swung past the zero stops 43 and be stopped by the stop pins 21^b or the stopping bar 41. The stop pin 21^a is not provided with such hump 55 nor does the trough-like bend 54 of a plate 38 extend adjacent to a stop pin 21^a so that by the actuation of a stop pin 21^a which is a zero stop pin, the plate 38 will not be deflected out of the path of a stop 37.

When it is desired to take a total, the sectors 36, as is usual with this type of machine, are then positioned by the cumulators 57 and not by stop pins such as the stop pins 21^a and 21^b of the present construction. For this purpose, the free movement of the sectors 36 must be permitted, which is accomplished by deflecting the plates 38 to one side. To this end, there is provided a pin 56 in the plate 46, which coöperates with the cam 58 on the shaft 59 suitably mounted in front of the slide-plate 46. The shaft 59 is provided with a lever 60 extending downwardly, the lower end of which is pivotally connected to the hook end 61 of the link 62, the rear end of which link 62 is pivotally connected to the upwardly extending arm 63 of the bell crank 64 which is journaled on the shaft 65 at its bend and has fixed to it a sleeve 66 mounted on said shaft 65. The horizontally extending arm 67 of the bell crank 64 is connected to the lower end of the link 68 which is connected at its upper end to the shifting bar 69. The shifting bar 69, as shown in Fig. 1, is connected to the cam link 70 which is operatively connected

at its upper end to the shaft 71 on which the cumulators 57 are mounted. The shifting bar 69, as is known in this type of machine, see my copending application, Serial No. 5 802,362, filed November 22, 1913, when depressed by the link 68, sets the cumulators 57 and the driving mechanism for taking a total.

For operating the cam 58 and setting the shifting bar 69, the shaft 65 is provided with a lever 72 fixed thereto (Fig. 2) which extends upwardly so that its upper end is disposed in engagement with the inner end of the push rod 73, the push rod 73 being slidably mounted in the bearing 74 fixed to the upper frame B and having a button 75 between which button 75 and the bearing 74 there is disposed a spring 76 by means of which the push rod is normally maintained in outwardly extending position. The shaft 65 has a lever 77 fixed to it adjacent to the bell crank 64 and having a pin 78 near its upper end which is disposed to engage the edge of the upwardly extending arm 63 of the bell crank 64 and actuate the same when the shaft 65 is rotated by the actuation of the lever 72 when the push rod 73 is pushed inwardly. When the bell crank 64 is thus actuated, it will in turn actuate the cam 58 thereby deflecting the plates 38 and permitting the free movement of the sectors 36 and simultaneously therewith setting the cumulators 57 by means of the arm 67 of the bell crank 64 actuating the link 68. When the machine is thus set, it is desirable that the same remain set until after a total is taken without requiring the continual engagement of the push button 75 by the operator. For this latter purpose, a lever 79 fixed to the sleeve 66 is provided, the sleeve 66 having a collar 80 fixed to the shaft 65 adjacent to it between which collar 80 and the lever 77 said sleeve is limited against lateral displacement. The end of the lever 79 is provided with a pin 81 which is in engagement with the upper edge of the head 82 of the latch 83. The latch 83 is pivotally connected at its lower end to the bracket 84 disposed adjacent to the driving shaft 85, which bracket 84 has a slot 86 in which rides the pin 87 formed on the forwardly extending portion 88 of the latch 83, which pin 87 extends through said bracket 84 sufficiently to lie in the path of movement of the sector 89 of the tabulating and totaling mechanisms, which sector 89 is fixed to the shaft 85. Disposed between the bracket 84 and the sector 89 there is provided a slide 90 which has a slot 91 in which play the pins 92 of the bracket 84, the forward end of which slide 90 has an upward extension 93 to which one end of the spring 94 is attached, the other end of which spring is attached to the portion 95 extending upwardly from the rear end of the bracket 84 by means of which

spring 94 the slide 90 is normally maintained in its rearward position. On the sector 89 there is formed a pin 96 which engages the upward extension 93 of the slide 90 and actuates said slide 90 in a forward direction when said sector 89 swings forwardly. The latch 83 is also provided with a rearwardly extending arm 97 to which one end of a spring 98 is attached, the other end of which spring is attached to the projection 99 formed on the frame B by means of which the latch 83 is normally maintained in its rearward position. When said latch 83 is depressed by engagement of its pin 87 with the rear edge of the sector 89, the upper edge of the head 82 will be disposed below the level of the lower edge of the slide 90. The operation of the foregoing anchoring means is as follows:—

When the button 75 is pushed in, the rocking shaft 65 will, by engagement of the pin 78 with the upper arm 63 of the bell crank 64, actuate the link 62 and the link 68, and by engagement of the pin 81 with the head 82 of the latch 83, swing said latch 83 forwardly against the tension of the spring 98 until the pin 81 passes under the hook 100 of the latch 83 and is anchored in position thereby. Thereupon the push button 75 may be released and the taking of a total will continue. Upon the rearward rocking of the sector 89, it will release the slide 90 to permit the spring 94 to actuate said slide 90 over and beyond the pin 81 so that the slide 90 will thereupon anchor the lever 79 in lowered position. Upon the continued rearward movement of the sector 89, its rear edge will engage the pin 87 of the latch 83 and swing said latch forwardly out of engagement with the pin 81 of the lever 79, thus positioning such latch 83 to return to initial movement as soon as the lever 79 is released. However, the lever 79, after being released by the latch 83, will still be anchored in lowered position by the slide 90, but upon the forward movement of the sector 89, the engagement of the pin 96 with the upward extension 93 of the slide 90 will draw said slide 90 forwardly, releasing the lever 79, whereupon the spring 101 will return the lever 79 and bell crank 67 to initial position.

The shifting bar 69 is operated by the sector 89 either to be moved to total-taking position or tabulating position. When the shifting bar 69 is in tabulating position, the notch 102 in its upper portion, is engaged by the pin 103 of the actuating lever 104 mounted on the shaft 105. On such shaft 105 there is also mounted a second lever 106 having a roller 107 mounted on its lower arm to be engaged by the sector 89. When the pin 103 is disposed in the notch 102 and the sector moves forwardly, its engagement with the roller 107 will rock the shaft 105 130

thereby rocking the lever 104 so that its pin 103 will shift the shifting bar 69 forwardly. On the other hand, when the shaft 65 has been actuated by the push button 75, so that the link 68 has drawn the shifting bar 69 downwardly, the notch 108 on the lower side of the shifting bar 69 will be engaged by the pin 109 of the lever 104. In this just-described engagement, the engagement of the sector 89 with the roller 107 on its rearward movement will rock the shaft 105 thereby rocking the lever 104 so that its pin 109 will shift the shifting bar 69 rearwardly.

It will be noted that by providing two sectors for each actuating mechanism comprising the bell-crank 64 and its related parts, a particular compact and simplified arrangement is made possible. To this end, each sector 89, except the first and last sectors, engage both a latch 83 of one actuating mechanism, and an actuating lever 105 of a preceding shifting bar 69, while the first sector only actuates a latch 83, and the last sector only actuates a lever 105 of a preceding shifting bar 69.

It is obvious that various changes and modifications may be made to the details of construction without departing from the general spirit or scope of the invention.

30 I claim:

1. In an accounting machine, the combination with a tabulating mechanism having a plurality of type-carrying members, a plurality of rows of integer stop pins for positioning said type-carrying members one row of stop pins for each carrying member, zero stops for normally positioning said members in zero printing position, pivotally mounted plates on which said zero stops are formed, and shoulders on said integer stop pins to rock said plates thereby to displace said zero stops out of carrying member stopping position when integer stop pins are actuated to permit carrying members to be positioned by such integer stop pins.

2. In an accounting machine, the combination with a tabulating mechanism having a plurality of type-carrying members, a plurality of rows of integer stop pins for positioning said type-carrying members, zero stops for normally positioning said carrying members in zero printing position, pivotally mounted plates on which said zero stops are formed, spring means for maintaining said pivotally mounted plates in zero stopping position, and shoulders on said integer stop pins to rock said plates out of carrying member stopping position thereby to displace said zero stops when integer stop pins are actuated to permit carrying members to be positioned by such integer stop pins.

3. In an accounting machine, the combination with a tabulating mechanism having a plurality of type-carrying members, a plurality of rows of integer stop pins for posi-

tioning said type-carrying members one row of stop pins for each carrying member, stops for normally positioning said carrying members in zero printing position, pivotally mounted plates on which said zero stops are formed, there being indentations in said plates, shoulders on said integer stop pins initially disposed in the indentations of said plates and adapted, when actuated, to rock said plates out of carrying member stopping position thereby to displace said zero stops to permit carrying members to be positioned by such integer stop pins.

4. In an accounting machine, the combination with a tabulating mechanism having a plurality of type-carrying members, a plurality of rows of integer stop pins for positioning said type-carrying members one row of stop pins for each carrying member, stops for normally positioning said carrying members in zero printing position, pivotally mounted plates on which said zero stops are formed, there being indentations in said plates, shoulders on said integer stop pins initially disposed in the indentations of said plates and adapted, when actuated, to engage said plates thereby to displace said zero stops to permit carrying members to be positioned by such integer stop pins, and zero stop pins without shoulders so that the actuation of said zero stop pins will not displace the zero stops of said pivotally mounted plates.

5. In an accounting machine, the combination with a tabulating mechanism having a plurality of type-carrying members, a plurality of rows of stop pins each row containing a zero stop pin and a plurality of integer stop pins, stops for normally positioning said carrying members in zero printing position, pivotally mounted plates on which said zero stops are formed, the actuation of said zero stop pins not affecting the position of said zero stops, there being indentations in said plates, shoulders on said integer stop pins initially disposed in the indentations of said plates and adapted, when actuated, to engage said plates thereby to displace said zero stops to permit carrying members to be positioned by such integer stop pins.

6. In an accounting machine, the combination with a tabulating mechanism having a plurality of type-carrying members, a frame, a plurality of rows of stop pins slidably mounted in said frame and adapted to be actuated to position said type-carrying members, there being recesses in the lower portions of said pins, and retractors disposed in said recesses and adapted to engage said stop pins to retract the same and lock them in initial position.

7. In an accounting machine, the combination with a tabulating mechanism having a plurality of type-carrying members, a frame, a plurality of rows of stop pins slid-

- ably mounted in said frame and adapted to be actuated to position said type-carrying members, said stop pins being arranged in pairs of rows, there being recesses in the lower portions of said stop pins, the recesses of each pair of rows facing one another, and retractors each disposed in the recesses of a pair of rows and adapted to engage said pair of rows to retract the same and lock them in initial position.
8. In an accounting machine, the combination with a tabulating mechanism having a plurality of type-carrying members, a frame, a plurality of rows of stop pins slidably mounted in said frame and adapted to be actuated to position said type-carrying members, there being recesses in the lower portions of said pins, retractors disposed in said recesses and adapted to engage said stop pins to retract the same and lock them in initial position, and means for actuating said stop pins to position said type-carrying members.
9. In an accounting machine, the combination with a tabulating mechanism having a plurality of type-carrying members, a frame, a plurality of rows of stop pins slidably mounted in said frame and adapted to be actuated to position said type-carrying members, said stop pins being arranged in pairs of rows, there being recesses in the lower portions of said stop pins, the retractors of each pair of rows facing one another, retractors each disposed in the recesses of a pair of rows and adapted to engage said pair of rows to retract the same and lock them in initial position, and means for actuating said stop pins to position said type-carrying members.
10. In an accounting machine, the combination with a tabulating mechanism having a plurality of type-carrying members, a plurality of rows of integer stop pins for positioning said type-carrying members one row of stop pins for each carrying member, zero stops for normally positioning said carrying members in zero printing position, pivotally mounted plates on which said zero stops are formed, there being indentations in said plates, shoulders on said integer stop pins initially disposed in the indentations of said plates and adapted, when actuated, to rock said plates thereby to displace said zero stops out of carrying member stopping position to permit a carrying member to be positioned by such integer stop pins, and means for actuating said plates when it is desired to take a total thereby to permit the free movement of said type-carrying members.
11. In an accounting machine, the combination with a tabulating mechanism having a plurality of type-carrying members, a plurality of rows of integer stop pins for positioning said type-carrying members, one row of stop pins for each carrying member, zero stops for normally positioning said carrying members in zero printing position, pivotally mounted plates on which said zero stops are formed, and means for rocking said plates when it is desired to take a total thereby to displace said zero stops out of carrying member stopping position to permit the free movement of said type-carrying members.
12. In an accounting machine, the combination with a tabulating mechanism having a plurality of type-carrying members, a plurality of rows of integer stop pins for positioning said type-carrying members one row of stop pins for each carrying member, zero stops, pivotally mounted plates on which said zero stops are formed, means for normally maintaining said plates in position so that said zero stops are disposed to position said carrying members in zero printing position, and means for rocking said plates when it is desired to take a total thereby to displace said zero stops out of carrying member stopping position and permit the free movement of said type-carrying members.
13. In an accounting machine, the combination with a tabulating mechanism having a plurality of type-carrying members, a plurality of rows of integer stop pins for positioning said type-carrying members one row of stop pins for each carrying member, zero stops, pivotally mounted plates on which said zero stops are formed, means for normally maintaining said plates in position so that said zero stops are disposed to position said carrying members in zero printing position, a reciprocally mounted plate in engagement with said pivotally mounted plates, a pin on said reciprocally mounted plate, a cam in engagement with said pin, and means for actuating said cam thereby to actuate said reciprocally mounted plate to actuate said pivotally mounted plate thereby to displace said zero stops and permit the free movement of said type-carrying members.
14. In an accounting machine, the combination with a tabulating mechanism having a plurality of type-carrying members, a plurality of rows of integer stop pins for positioning said type-carrying members one row of stop pins for each carrying member, zero stops, pivotally mounted plates on which said zero stops are formed, means for normally maintaining said plates in position so that said zero stops are disposed to position said carrying members in zero printing position, means for actuating said plates when it is desired to take a total thereby to displace said zero stops and permit the free movement of said type-carrying members, and means for temporarily maintaining said plate-actuating means in position where said pivotally mounted plates will permit free movement of said type-carrying members.
15. In an accounting machine, the combination with a tabulating mechanism having a plurality of type-carrying members, a plurality of rows of integer stop pins for positioning said type-carrying members one row of stop pins for each carrying member, zero stops, pivotally mounted plates on which said zero stops are formed, means for normally maintaining said plates in position so that said zero stops are disposed to position said carrying members in zero printing position, and means for rocking said plates when it is desired to take a total thereby to displace said zero stops out of carrying member stopping position and permit the free movement of said type-carrying members.

nation with a tabulating mechanism having a plurality of type-carrying members, a plurality of rows of integer stop pins for positioning said type-carrying members one row 5 of stop pins for each carrying member, zero stops, pivotally mounted plates on which said zero stops are formed, means for normally maintaining said plates in position so that said zero stops are disposed to position 10 said carrying members in zero printing position, a reciprocally mounted plate in engagement with said pivotally mounted plates, a pin on said reciprocally mounted plate, a cam in engagement with said pin, means for 15 actuating said cam thereby to actuate said reciprocally mounted plate to actuate said pivotally mounted plates thereby to displace said zero stops and permit the free movement of said type-carrying members, a shaft 20 on which said cam is mounted, a link operatively connected to said shaft, and means for actuating said link thereby to actuate said pivotally mounted plates to displace said zero stops and permit the free movement 25 of said type-carrying members.

16. In an accounting machine, the combination with a tabulating mechanism having a plurality of type-carrying members, a plurality of rows of integer stop pins for positioning said type-carrying members one row 30 of stop pins for each carrying member, zero stops, means for normally maintaining said zero stops in position so that they will position said carrying members in zero printing 35 position, means for temporarily displacing said zero stops when it is desired to take a total so as to permit the free movement of said type-carrying members at such time, said latter means comprising a reciprocally 40 mounted plate operatively connected to said stop pins, a pin on said reciprocally mounted plate, a cam in engagement with said pin, and means for actuating said cam thereby 45 to actuate said reciprocally mounted plate to displace said zero stops and permit the free movement of said type-carrying members.

17. In an accounting machine, the combination with a tabulating mechanism having a plurality of type-carrying members, a plurality of rows of integer stop pins for positioning said type-carrying members one row 50 of stop pins for each carrying member, zero stops, means for normally maintaining said zero stops in position so that they will position said carrying members in zero printing 55 position, means for temporarily displacing said zero stops when it is desired to take a total so as to permit the free movement of said type-carrying members at such time, said latter means comprising a reciprocally 60 mounted plate operatively connected to said stop pins, a pin on said reciprocally mounted plate, a cam in engagement with said pin, a shaft on which said cam is mounted, a link 65 operatively connected to said shaft,

operatively connected to said shaft, a second shaft, a bell crank on said second shaft pivotally connected to said link, a lever on said shaft, and means for actuating said lever thereby to actuate said bell crank to 70 actuate said link.

18. In an accounting machine, the combination with a tabulating mechanism having a plurality of type-carrying members, a plurality of rows of integer stop pins for positioning said type-carrying members one row 75 of stop pins for each carrying member, zero stops, means for normally maintaining said zero stops in position so that they will position said carrying members in zero printing position, means for temporarily displacing said zero stops when it is desired to take a total so as to permit the free movement of said type-carrying members at such time, said latter means comprising a reciprocally 80 mounted plate operatively connected to said stop pins, a pin on said reciprocally mounted plate, a cam in engagement with said pin, a shaft on which said cam is mounted, a link operatively connected to said shaft, a second shaft, a bell crank on said second shaft pivotally connected to said link, a stop 85 fixed to said second shaft, a lever on said second shaft, and means for actuating said lever whereby said stop will engage and 90 actuate said bell crank to actuate said link.

19. In an accounting machine, the combination with a tabulating mechanism having a plurality of type-carrying members, a plurality of rows of integer stop pins for positioning said type-carrying members one row 95 of stop pins for each carrying member, zero stops, means for normally maintaining said zero stops in position so that they will position said carrying members in zero printing position, means for temporarily displacing said zero stops when it is desired to take a total so as to permit the free movement of said type-carrying members at such time, said latter means comprising a reciprocally 100 mounted plate operatively connected to said stop pins, a pin on said reciprocally mounted plate, a cam in engagement with said pin, a shaft on which said cam is mounted, a link operatively connected to said shaft, a second shaft, a bell crank on said second shaft pivotally connected to said link, a stop fixed to said second shaft, a lever on said second shaft, means for actuating said lever whereby said stop will engage 105 and actuate said bell crank to actuate said link, and means for temporarily anchoring said bell crank in actuated position.

20. In an accounting machine, the combination with a tabulating mechanism having 115 a plurality of type-carrying members, a plurality of rows of integer stop pins for positioning said type-carrying members one row 120 of stop pins for each carrying member, zero stops, means for normally maintaining 125 said zero stops in position so that they will position said carrying members in zero printing position, means for temporarily displacing said zero stops when it is desired to take a total so as to permit the free movement of said type-carrying members at such time, said latter means comprising a reciprocally 130 mounted plate operatively connected to said stop pins, a pin on said reciprocally mounted plate, a cam in engagement with said pin,

- said zero stops in position so that they will position said carrying members in zero printing position, means for temporarily displacing said zero stops when it is desired 5 to take a total so as to permit the free movement of said type-carrying members at such time, said latte: means comprising a reciprocally mounted plate operatively connected to said stop pins, a pin on said reciprocally mounted plate, a cam in engagement with said pin, a shaft on which said cam is mounted, a link operatively connected to said shaft, a second shaft, a bell crank on said second shaft pivotally connected to said 10 link, a stop fixed to said second shaft, a lever on said second shaft, means for actuating said lever whereby said stop will engage and actuate said bell crank to actuate said link, and means for temporarily anchoring said bell crank in actuated position, said anchoring means comprising a second lever fixed to said second shaft, a stop on said second lever, means to engage said stop and anchor the same when said bell crank is actuated, 15 and an oscillating sector for actuating said stop engaging means out of engagement with said stop to release said bell crank.
- 20 21. In an accounting machine, the combination with a tabulating mechanism having a plurality of type-carrying members, a plurality of rows of integer stop pins for positioning said type-carrying members one row of stop pins for each carrying member, zero stops, means for normally maintaining said zero stops in position so that they will position said carrying members in zero printing position, means for displacing said zero stops when it is desired to take a total so as to permit the free movement of said type-carrying members at such time, said displacing means comprising a shaft, a bell crank on said shaft pivotally connected to said displacing means, a stop fixed to said shaft, a lever fixed on said shaft, means for actuating said lever whereby said stop will engage and actuate said bell crank to actuate said displacing means, means for temporarily anchoring said bell crank in actuated position, said anchoring means comprising a second lever fixed to said shaft, a stop on said second lever, means to engage said stop and anchor the same when said bell crank is actuated, and an oscillating sector for actuating said stop engaging means out of engagement with said stop to release said bell crank.
- 25 26 27 28 29 30 35 36 37 38 39 40 45 46 47 48 49 50 55 56 57 58 59 60 65 66 67 68 69 70 75 76 77 78 79 80 85 86 87 88 89 90 95 96 97 98 100 105 110
21. In an accounting machine, the combination with a tabulating mechanism having a plurality of type-carrying members, a plurality of rows of integer stop pins for positioning said type-carrying members one row of stop pins for each carrying member, zero stops, means for normally maintaining said zero stops in position so that they will position said carrying members in zero printing position, means for displacing said zero stops when it is desired to take a total so as to permit the free movement of said type-carrying members at such time, said displacing means comprising a shaft, a bell crank on said shaft pivotally connected to said displacing means, a stop fixed to said shaft, a lever fixed on said shaft, means for actuating said lever whereby said stop will engage and actuate said bell crank to actuate said displacing means, means for temporarily anchoring said bell crank in actuated position, said anchoring means comprising a second lever fixed to said shaft, a stop on said second lever, means to engage said stop and anchor the same when said bell crank is actuated, and an oscillating sector for actuating said stop engaging means out of engagement with said stop to release said bell crank.
22. In an accounting machine, the combination with a tabulating mechanism having a plurality of type-carrying members, a plurality of rows of integer stop pins for positioning said type-carrying members one row of stop pins for each carrying member, zero stops, means for normally maintaining said zero stops in position so that they will position said carrying members in zero printing position, means for displacing said zero stops when it is desired to take a total so as to permit the free movement of said type-carrying members at such time, said displacing means comprising a shaft, a bell crank on said shaft pivotally connected to said displacing means, a stop fixed to said shaft, a lever fixed on said shaft, means for actuating said lever whereby said stop will engage and actuate said bell crank to actuate said displacing means, means for temporarily anchoring said bell crank in actuated position, said anchoring means comprising a second lever fixed to said shaft, a stop on said second lever, means to engage said stop and anchor the same when said bell crank is actuated, and an oscillating sector for actuating said stop engaging means out of engagement with said stop to release said bell crank.
23. In an accounting machine, the combination with a tabulating mechanism having a plurality of type-carrying members, a plurality of rows of integer stop pins for positioning said type-carrying members one row of stop pins for each carrying member, zero stops, means for normally maintaining said zero stops in position so that they will position said carrying members in zero printing position, means for displacing said zero stops when it is desired to take a total so as to permit the free movement of said type-carrying members at such time, means for temporarily anchoring said displacing means in actuated position, said anchoring means comprising a shaft, a lever fixed to said shaft, a stop on said lever, and means to engage said stop and anchor the same when said displacing means has been actuated, and an oscillating sector for actuating said stop engaging means out of engagement with said stop to release said displacing means.

JAMES POWERS.
